(57) **CLAIM**

The ornamental design for a hyperbaric chamber gurney storage device, as shown and described.

DESCRIPTION

FIG. 1 is a front perspective view of a hyperbaric chamber gurney storage device showing our new design;

FIG. 2 is a front elevational view thereof;

FIG. 3 is a perspective view thereof with the gurney removed therefrom;

FIG. 4 is an end elevational view thereof with the gurney removed therefrom;

FIG. 5 is a perspective view with the gurney and hyperbaric chamber removed therefrom;

FIG. 6 is a front end elevational view thereof;

FIG. 7 is a rear end elevational view thereof;

FIG. 8 is a top plan view thereof;

FIG. 9 is a side elevational view thereof; and,

FIG. 10 is a bottom plan view thereof.

The broken lines in FIGS. 1-4 illustrate unclaimed environment only and form no part of the claimed design.
